UNITED STATES PATENT OFFICE.

JOHN W. IRVIN, OF FRANKLIN, NEBRASKA, ASSIGNOR OF TWO-FIFTHS TO H. J. WAY,
OF HASTINGS, NEBRASKA.

VALVE-IN-HEAD MOTOR.

Application filed January 11, 1923. Serial No. 612,053.

To all whom it may concern:

Be it known that I, JOHN W. IRVIN, a citizen of the United States of America, residing at Franklin, in the county of 5 Franklin and State of Nebraska, have invented new and useful Improvements in Valve-in-Head Motors, of which the following is a specification.

The object of the invention is to provide 10 a valve-in-head motor wherein the operation of the valves may be accomplished by simplified mechanism from which the objectionable knock or tap may be eliminated and wherein the resistance due to friction 5 and inertia may be minimized and a perfect condition of lubrication may obtain at all times; and with this object in view the invention consists in a construction and combination of parts of which a preferred 20 embodiment is shown in the accompanying drawings, wherein:—

Figure 1 is a vertical sectional view of the contents of a motor having a construction embodying the invention.

25 Figure 2 is a transverse sectional view of the same.

Figure 3 is a horizontal sectional view thereof.

30 Figure 4 is a vertical sectional view of the rear end of the motor.

The cylinder head 10, valves having the stems 11 and seating springs 12 are of conventional construction.

Associated with the valve stems in operative relation thereto is a cam shaft 13 having the cams 14 for respective actuation of the valve stems to unseat the valves in timed relation with the operation of the cylinder pistons (not shown). Interposed 35 between the cam shaft and the valve stems are valve fingers 15 forming elements of rockers of which the knuckles or heads 16 are mounted upon a pivot rod 17 extending longitudinally of the motor and are seated 40 in an oil channel 18 also extending longitudinally of the motor and formed in the construction illustrated in an upward enlargement 19 of the cylinder head.

The valve fingers are provided at their 50 free ends with adjusting bolts 20 forming tappets for direct contact with the valve stems and are also provided in the paths of the cams 14 with cushioned contact elements 21 consisting preferably of raw-hide inserts or pads having a durable wear-

ing quality and affording a noise eliminating contact for the cams.

Furthermore extended longitudinally in overhead relation with the cam shaft is an oil feed tube 22 orificed at intervals as 55 shown at 23 in the vertical planes of the cams so as to provide a drip of oil for each cam to be conveyed thereby to the surface with which it contacts. The feed tube may be supplied from any suitable source and 60 by any preferred pressure device such as a pump (not shown) and at its rear end it is provided with a branch 24 discharging into the oil channel 18 in which the heads or knuckles of the valve fingers are seated. 65 This oil channel being extended to the front end of the motor to insure a supply of oil to the rockers throughout the series, discharges into the crank case through the guard 25 which is provided for the chain 70 26 by which motion is communicated from the crank shaft to the cam shaft. While this is a suitable preferred method of completing the circulation of the oil to the end that there may be no waste thereof while 75 insuring a supply to the essential parts of the valve operating mechanism, it will be understood that modifications of this arrangement may be adopted to suit different types of motors provided the principle of 80 circulation to insure the deposit of the surplus oil in the crank case is observed to the end that there may be no excessive and unnecessary expenditure of oil due to the continuous supply thereof to the elements 85 of the valve mechanism.

The overhead cam shaft rockers and related devices including the valve stems and their spouts, are preferably arranged within a housing 27 surmounting the cylinder head and interiorly accessible by means of a removable cap plate 28.

Having described the invention, what is claimed as new and useful is:—

1. A valve-in-head motor having an overhead valve actuating cam shaft, rockers provided with fingers interposed between the valve stems and the cams on the cam shaft, means for operating said cam shaft, and cushioned contact elements consisting of pads having a durable wearing quality inset in the rockers and affording noise eliminating contact for the cams.

2. A valve-in-head motor having an overhead valve actuating cam shaft, rockers 110

- provided with valve fingers interposed between the valve stems and the cams of the cam shaft, means for operating said cam shaft, an oil channel extending longitudinally of the motor and cross sectionally conforming to the rockers, means for pivotally mounting the rockers concentric with the channel, and means for supplying lubricant to the channel.
- 10 3. A valve-in-head motor having an overhead valve actuating cam shaft, rockers having valve fingers interposed between the valve stems and the cams of the cam shaft, means for operating said shaft and
- 15 an orificed oil feed tube arranged in overhead relation with the cam shaft, the rockers being mounted in a continuous oil

channel in communication with said oil feed tube.

4. A valve-in-head motor having an overhead valve actuating cam shaft, rockers having valve fingers interposed between the valve stems and the cams of the cam shaft, means for operating said shaft and an orificed oil feed tube arranged in overhead relation with the cam shaft, the rockers being mounted in a continuous oil channel in communication with said oil feed tube and disposed to discharge into the crank case.

20 25 30 In testimony whereof he affixes his signature.

JOHN W. IRVIN.
